UNITED STATES PATENT OFFICE.

EMIL A. STRAUSS, OF CHICAGO, ILLINOIS.

VAULT CONSTRUCTION.

1,376,839.

Specification of Letters Patent.

Patented May 3, 1921.

Application filed April 21, 1919. Serial No. 291,596.

To all whom it may concern:

Be it known that I, EMIL A. STRAUSS, a citizen of the United States, residing at Chicago, in the county of Cook and State of Illinois, have invented a certain new and useful Improvement in Vault Construction, of which the following is a full, clear, concise, and exact description, reference being had to the accompanying drawings, forming a part of this specification.

My invention relates to vaults and particularly to an improved reinforced wall construction for use in connection with vaults of the security or burglar-proof type.

The prior art walls of this general description have invariably been constructed of concrete reinforced with steel rails or various types of reinforcing rods. Great difficulty has been experienced in reinforcing a concrete wall with steel rails so as to effectively prevent penetration of the concrete in such a manner as to entirely avoid the reinforcing structure. Penetration of the concrete in such manner as to encounter

little or no reinforcing resistance—as has heretofore been a comparatively simple matter—obviously facilitates removal of the concrete surrounding a particular rail or plurality of rails, whereupon access to the vault may be readily gained by cutting away—as by means of an acetylene torch or the like—the necessary rail or rails.

In attempting to overcome such disadvantages the steel rails are frequently arranged so close together that the flanges of the rails present a continuous line of cleavage along the sides of the reinforcing structure; making it practically impossible to embed each of the various rails of the reinforcing structure in a substantially monolithic concrete wall. Thus the concrete instead of embedding each of the various rails to securely interlock the same, forms in effect, a closure comprising independent concrete walls adjacent the sides of the reinforcing structure. I have observed that it is a simple matter to cut through such a concrete wall whereupon the entire reinforcing structure is exposed and not being interlocked with concrete can be readily penetrated.

My invention aims to provide a burglar-proof wall construction wherein not only will maximum reinforcing resistance be offered against penetration of the wall, but the concrete portion of the wall will be substantially monolithic; the various reinforcing units being embedded and effectively interlocked by means of the concrete.

My invention aims further to provide a burglar-proof reinforced wall construction of the simplest character consistent with strength and effectiveness.

In accordance with the teachings of my invention I have provided for the construction of a security or burglar-proof vault, the walls of which are composed of H columns, I beams or beams of similar cross section embedded and securely interlocked in concrete or the like to form a solid wall. I have further provided for binding the reinforcing beams along their upper and lower edges, within their length and at all corners by means of suitable angle irons, tie rods or the like.

Other aims of my invention not hereinbefore set forth will appear from the following detailed description and the claims, taken with an inspection of the accompanying drawings, in which—

Figure 1 shows in vertical section an illustrative embodiment of my invention;

Fig. 2 is a horizontal sectional view taken substantially on the line 2—2 of Fig. 1;

Fig. 3 is an enlarged detailed fragmentary vertical section of the steel reinforcing structure;

Fig. 4 is an enlarged detailed horizontal fragmentary section of the same; and

Fig. 5 is a fragmentary section of a modification.

Although my invention is primarily intended for use in connection with security vaults and the like it will be apparent as this description proceeds, that the invention will admit of broader application than the specific use which I shall describe as an instance of its employment.

As shown in Fig. 1 the base or floor 1 of the vault is preferably reinforced in substantially the same manner as the side and top walls. Thus a solid foundation is pro-

vided through which unauthorized entrance to the vault from beneath is effectively prevented.

The floor or base reinforcing structure 5 comprises a plurality of horizontal beams 2—of **H**, **I** or similar cross section—arranged substantially the width of a beam apart therethrough. The distance between the beams 2 may of course be varied to suit various 10 installations. The beams 2 may be supported at their opposite ends by means of a pair of similar beams 3 arranged transversely therebeneath although it is to be understood that the beams 2 can be arranged directly in the concrete base or floor 1 if so desired.

A plurality of beams 4 similar to the beams 2 are arranged between the beams 2 in staggered relation thereto as shown. The beams 20 4 may be supported by means of suitable beams 5 arranged transversely beneath their opposite ends if so desired, although this is not essential. The floor or base reinforcing structure thus provided is interlocked throughout by means of the concrete wall 1. While the concrete wall thus provided is substantially monolithic, penetration thereof—in such manner as to encounter little or no reinforcing resistance—is effectively 30 prevented.

Installation of the floor or base is greatly facilitated by filling in the concrete to the proper depth for supporting the beams 2 in the position shown. Upon allowing the concrete thus filled to set, installing the beams 35 3 and arranging the beams 2 thereacross, this depth of concrete is increased sufficiently to support the beams 4 at a relatively greater height than the beams 2 substantially as shown in Fig. 1.

Upon completion of the floor or base reinforcing structure in this manner an angle iron binding element 6 is arranged about the outer edges of the beams 2 and bolted or 45 otherwise suitably secured thereto. The horizontal beams 2 are of relatively greater length than the horizontal beams 4 whereby the binding element 6 can be arranged transversely across the opposite ends of the beams 50 2; clearing the relatively shorter beams 4. An angle iron binding element 7 similar to but relatively smaller than the angle iron binding element 6 is arranged about the beams 4 substantially as shown in Fig. 1 and 55 suitably secured thereto.

The upright columns 8 and 9—of **H**, **I** or similar cross section—are then arranged about the outer edges of the floor or base reinforcing structure in staggered order 60 substantially as shown in Figs. 1 and 2. The columns 8 are securely bound together adjacent the lower edges of their outer flanges by means of the angle iron binding element 6, the outer flanges of the columns 8 being

bolted to the vertical flange of this binding element 6 as by means of suitable bolts 10, (Fig. 4). The columns 9 are securely bound together adjacent the lower edges of their inner flanges by means of the angle iron binding element 7 being bolted to the vertical flange of the binding element 7 by means of suitable bolts 11.

As clearly shown the upper edges of the upright columns 8 and 9 respectively are likewise securely bound together. An angle 75 iron binding element 12, similar to the binding element 6 but inverted relative thereto, is securely bolted about the outer flanges of the columns adjacent the upper edges thereof. The upper edges of the columns 80 9, the height of which columns 9 is less than the height of the columns 8 (Fig. 1) are bound together by means of an angle iron binding element 14 bolted or otherwise suitably secured therealong.

The angle iron binding members 12 and 14, which angle iron binding members are similar to the binding members 6 and 7, comprise (as shown in Fig. 2) angle iron corner pieces connected together by suitable angle 90 irons extending therebetween. These angle irons are welded, bolted or otherwise suitably joined to the angle iron corner pieces to provide a continuous angle iron binding element about the upper, lower, inner and 95 outer edges respectively of the entire reinforcing structure.

In addition to binding the outer reinforcing wall composed of the columns 8 and the inner reinforcing wall composed of the 100 columns 9 independently I provide for binding the columns 8 and 9 securely together by means of a plurality of tie rods 16. As shown in Fig. 4, these tie rods 16, which are preferably provided with suitable burn 105 resisting sleeves (not shown) extend through the columns 8 adjacent their inner flanges and continue through the columns 9 adjacent their outer flanges. Suitable nuts 17 engage the opposite ends of the tie rods 16, binding 110 the upright reinforcing columns 8 and 9 securely together at the various corners of the structure.

The binding elements 12 and 14 not only serve to bind the outer and inner upper 115 edges of the columns 8 and 9 respectively but in addition serve to support the opposite ends of the horizontal ceiling reinforcing beams 16' and 17 (Figs. 1 and 2). These horizontal ceiling reinforcing beams 120 16' and 17 span the binding members 12 and 14 respectively and are bolted or otherwise suitably secured at their opposite ends to these binding members as shown in Fig. 3. These ceiling reinforcing beams 16' and 17 125 are preferably bound together by means of suitable tie rods 24 (Fig. 3) as are the floor or base reinforcing beams 2 and 4.

- It will now be apparent that by reason of the relative different heights of the binding members 12 and 14 that the horizontal ceiling reinforcing beams 16' and 17 will be arranged in staggered order substantially as described in connection with the base or floor reinforcing beams 2 and 4. The beams 17 are as hereinbefore pointed out relatively shorter than the beams 16' their opposite ends terminating at the inner edge of the outer upright columns, 8, as shown in Fig. 2, while the horizontal beams 16' are of such length as to span the outer binding member 12 to which binding member they are suitably secured as hereinbefore pointed out.
- Upon completion of the reinforcing structure the concrete is filled in to form the ceiling 18, vertical walls 20 and to complete or finish the floor or base 1. Obviously the practically monolithic concrete structure thus provided completely surrounds each of the various reinforcing beams, effectively interlocking the same to provide a wall of great strength. As the present invention is not concerned with the particular manner of filling in the concrete, I do not consider that it is necessary to describe this feature in detail as the same is old and well understood by those skilled in the art.
- It will now be apparent that the burglar-proof wall construction thus provided is of the simplest character consistent with strength and effectiveness.

In the modification shown in Fig. 5 the outer and inner reinforcing beams 8' and 9' respectively are arranged in independent parallel spaced rows, an intermediate row of beams 22 being arranged therebetween substantially as shown. Thus the outer flanges of the beams 22 are arranged between the beams 8', the inner flanges of these beams 22 being arranged between the beams 9'. Upon installation of the concrete wall these various beams are effectively interlocked, providing a unitary structure exceedingly difficult to penetrate. The beams 8', 22 and 9' can be bound together—if so desired—by means of tie rods 23 substantially as described in connection with the embodiment illustrated in Figs. 1, 2, 3 and 4.

While I have described my invention in connection with the details of a particular embodiment I do not intend thereby to limit the invention to such details as I am aware, and contemplate that modifications and changes may be made without departing from the invention which is set out in the appended claims.

I claim:

1. A vault wall comprising a body of concrete, and a series of similar I-beams embedded therein with their longitudinal edges parallel to and distanced from the wall faces, each two I-beams being spaced from

and staggered relative to each other with the edges of all their adjacent flanges disposed substantially equidistantly substantially in the same plane.

2. In combination, a series of reinforcing beams, a second series of reinforcing beams arranged in staggered order therebetween, binding means for said first series of beams, independent binding means for said second series of beams, a plurality of tie rods for binding said independent series of beams together, and a closure for said structure comprising a substantially monolithic concrete wall embedding said structure and filling the spaces between said beams.

3. In a burglar-proof vault construction, the combination of a series of reinforcing columns having a binding member arranged thereabout, a second series of reinforcing columns of a height substantially greater than the height of said first series of columns, a binding member arranged about said second series of columns, a plurality of reinforcing beams arranged across said first binding member, and a plurality of reinforcing beams arranged across said second binding member, the difference in height between said first and second series of reinforcing columns positioning said second series of reinforcing beams in staggered order between said first series of reinforcing beams.

4. In a burglar-proof vault construction the combination with a base formed of a plurality of beams arranged in staggered order, of a series of reinforcing columns having a binding member arranged about the lower ends thereof and connected to said base, a second series of reinforcing columns arranged in staggered order between said first series of reinforcing columns, a binding member arranged about the lower ends of said second series of reinforcing columns and connected to said base and means for binding said first and second series of columns and said base reinforcing beams together.

5. In a burglar proof vault reinforcing structure, a series of substantially upright wall columns, a second series of substantially upright wall columns terminating at different heights than said first wall columns, a series of ceiling beams carried by said first wall columns, a second series of ceiling beams carried by said second wall columns, the different points of termination of said columns effecting a staggered arrangement of said ceiling beams.

6. In a burglar proof vault a reinforcing structure including, a base beam, a substantially upright wall column mounted thereupon, a second base beam staggered relative to said first base beam, a second substantially upright wall column mounted upon said

second base beam, the upper ends of said substantially upright wall columns terminating at different heights and ceiling beams carried by said wall columns the different 5 points of termination of said columns effecting a staggered arrangement of said ceiling beams.

7. In a burglar proof vault reinforcing structure, a series of base beams, a second series of base beams arranged in staggered 10

order therebetween, a series of substantially upright wall columns carried by said first series of base beams and a second series of substantially upright wall columns carried by said second series of base beams and arranged in staggered order between said first series of wall columns. 15

In witness whereof I hereunto subscribe my name this 16th day of April, 1919.

EMIL A. STRAUSS.
